UNITED STATES PATENT OFFICE.

FREDERICK W. GILLARD, OF BROOKLYN, NEW YORK.

COMBINED RAILROAD FARE AND TRANSFER TICKET.

SPECIFICATION forming part of Letters Patent No. 717,984, dated January 6, 1903.

Application filed June 8, 1901. Serial No. 63,782. (No model.)

To all whom it may concern:

Be it known that I, FREDERICK W. GILLARD, a citizen of the United States, residing at Brooklyn, in the State of New York, have invented certain new and useful Improvements in a Combined Railroad Fare and Transfer Ticket; and I do hereby declare the following to be a full, clear, and exact description of the invention, such as will enable others skilled in the art to which it appertains to make and use the same.

This invention relates to improvements in tickets, and more particularly to a form of ticket having a plurality of functions—such, for instance, as serving the purposes of a transfer in addition to those of a ticket.

The object in view is the production of a book of tickets each attached to its respective stub, each stub being provided with means for automatically accounting for all preceding tickets, together with its respective ticket and all subsequent tickets.

The present invention consists of certain novel constructions, combinations, and arrangements of parts, as will be hereinafter more fully described and claimed.

In the accompanying drawings, Figure 1 represents a top plan view of a ticket and stub embodying the features of the present invention. Fig. 2 represents a similar view of a slightly-modified form of the same. Fig. 3 represents a top plan view of a package of my improved tickets in an extended condition reduced in size for the saving of space; and Fig. 4 represents a perspective view of a book composed of suitable backs and stubs, each of the stubs carrying a package of my improved tickets, the illustration being also on a similarly-reduced scale.

In the use of railway-tickets it has been found desirable to provide means for counter-checking and accounting for every ticket issued by the company and received by a conductor and for showing receipts of cash by the conductor. The present invention contemplates means for accomplishing these results to the best advantage and at the least expense and a minimum of labor.

In Fig. 1 of the accompanying drawings the numeral 1 indicates a suitable ticket detachably secured to a stub 2, which latter is provided with any suitable binding extension,

as 3. A suitable space, as 4, is provided upon ticket 1 for the insertion of directions regarding the use of the ticket as such or as a transfer, the wording given on the drawing upon said space being such as to limit the ticket to transfer purposes; but of course any preferred directions may be inserted in said space. As seen at 5, the direction in which the car carrying the conductor issuing the ticket is bound is indicated, and it will be understood that when used as a transfer I will employ similar marks at any suitable points on the ticket for indicating the direction in which the transferred passenger is to travel. At one point on the space of the ticket, preferably at the outer end, as shown at 6, is provided a suitable calendar, the months and days of which are adapted to be perforated by the punch of the conductor for limiting the time for using the transfer.

In order to compel the passenger to board the next connecting car, I contemplate the provision of a suitable time-table, as indicated at 7, whereby the hour and fractions thereof may be indicated. This time-table comprises, preferably, a double row of figures indicating the hours of the day before and after the sun has passed the meridian. I may of course employ either row of figures for indicating either the forenoon or afternoon; but, as indicated, I prefer to utilize the upper row for indicating the morning and the lower row the evening. Above and below the said rows of figures I provide suitable spaces ruled with lines, as 8 and 9, which form series of vertically-extending blocks for purposes hereinafter set forth. At one end of the time-table 7 and extending transversely thereof are provided suitable indications of fractions of the hour, as at 10 and 11, each of said indications appearing opposite one of the series of blocks 8 or 9. Of course it will be seen that I prefer to place the letters "A. M." and "P. M." upon the time-table in a suitable position to indicate which row of figures represent the hours of the forenoon and which the afternoon. As indicated at 11', I may provide, if desired, suitable numbers indicating fractions of an hour to be employed for extending the time of the transfer in case of accident upon the road preventing its immediate use, and I may also provide a suitable point hav-

ing any desired indication for being cancelled by the conductor receiving the transfer, as seen at 12.

The ticket illustrated in Fig. 1 is to be employed on lines charging cash fares, and for the sake of illustration we will presume the fare to be five cents. The conductor will be provided with any desired number of packages of these tickets bound together at 3, and upon receipt 10 of a fare will inquire of the passenger as to whether or not he desires a transfer. Upon receiving an affirmative answer, supposing the hour at which the car carrying the present conductor is to intersect the line of transfer to be 9.45 a. m., the said conductor will 15 punch the ticket within the block "9," (indicated at 13,) whereby both the hour and fraction thereof will be clearly shown. Had the time been nine o'clock, the perforation would 20 have been made through that figure "9," thus showing that no fraction of the hour was intended to be indicated. It will of course be understood that the conductor at any suitable time will perforate calendar 6 at the 25 necessary points for limiting the transfer to the particular month and day. After the issuance of the transfer if an accident should occur on the line whereby the car is delayed the conductor upon request of the passenger 30 will perforate a suitable figure in the scale 11' for extending the time of the transfer. Upon presenting the transfer to the conductor on the connecting car the same is adapted to be perforated at a suitable point, 35 as 12, for preventing further use of the same and then retained by the conductor to be returned to the company. Assuming now that the passenger did not desire a transfer, the conductor would simply tear the ticket trans- 40 versely, as shown in dotted lines at 14, retaining the outer end to be returned to the company, while the inner end remains connected to the stub 2.

Of course I will provide a suitable number, 45 as at 15 15, upon the stub and ticket for the purpose of counter-checking upon the return of the ticket to the company.

With whatever form of ticket I employ I also contemplate the use of stub 2, which 50 shall be so prepared as to automatically audit the accounts of the conductor. In order to accomplish this, I indicate at a suitable point on the stub the value of its corresponding ticket plus the values of all tickets of the preceding stubs, as at 16 or at 16^a, as desired. I also indicate, as at 17, the value of all the 55 tickets of the several following stubs within the same binding. Opposite these indications of value I may place any suitable words 60 of explanation, as illustrated, which in the case of the preceding values plus the value of the ticket of the particular stub may be either "Fares collected" or "Must be returned to company with," and the words "Un- 65 issued fares" are preferably printed opposite the indication, as at 17, of the value of the succeeding tickets. By this means the con-

ductor has only to turn to his last stub in order to readily ascertain what amount is due from him to the company on tickets already 70 sold and what is the total value of the tickets still remaining in his hands.

In employing the cash-fare ticket I of course make packages of single tickets; but when an uneven rate is charged—that is to say, 75 where six or more tickets are sold at a given price, the cash fare being greater than the price of the individual ticket when purchased in packages of six or more—I preferably arrange a plurality of my improved tickets as 80 best illustrated in Figs. 3 and 4. These tickets of course may each be printed similarly to ticket 1, except that a coupon, as 18, is detachably secured to the same, as hereinafter described. There is another slight difference 85 necessitated by this arrangement consisting of a power indicated upon each of the tickets in addition to the regular serial number corresponding to number of the stub, as indicated at 19 19. These powers of course may 90 be omitted, but are preferred for convenience. As seen in Fig. 4, the tickets, as 1' 1', are folded upon each other to assume a book form, and one of the tickets 1' is detachably secured to the stub 2', the said stub 2' being 95 of a thickness equivalent to the thickness of the six tickets 1', or the stub 2' may be the thickness of a single ticket and a piece of cardboard or other backing, as 20', inserted between each two of the said stubs, said 100 backing being of equivalent thickness to five of the tickets. The stub 2' is of course provided with indications of preceding and following ticket values, as at 16' and 17', similar to those shown on stub 2. To more clearly 105 illustrate my improved system of automatic auditing, I would state that, as illustrated in Fig. 4, presuming each package of six tickets to be of the value of twenty-five cents and that seven packages of tickets are bound 110 within one cover, the first stub would show, as seen in dotted lines in said Fig. 4, the figures "25," indicating the value of its ticket, no other ticket preceding it, and the figures "150," indicating the value of the 115 six succeeding packages of tickets. The second stub will be provided with the numbers "50," indicating the value of its package of tickets added to the value of the package of tickets of the preceding stub, and "125," indicating the value of the succeeding five packages of tickets. It will be seen that this arrangement of indications on the stub of the various packages of tickets will obviate the necessity of any calculation for attaining the 120 conductor's account after a day's work, the stub of the last-used package of tickets clearly indicating said account.

It will be seen that when the first ticket 1' of a package is detached from the others, the 130 remaining five tickets being delivered to the passenger and the said first ticket is desired to be used as a transfer, as hereinbefore described with reference to ticket 1, the con-

ductor will simply detach coupon 18 and retain the same to be returned to the company as a voucher, the said first ticket 1' being then prepared as before described for use as 5 a transfer and handed to the passenger.

It has been found desirable, in view of cheaper rates, to issue commutation-tickets, and I find it convenient and preferable to provide such a ticket in connection with the hereinbefore-described arrangement of ticket and transfer. The last-mentioned ticket is illustrated in Fig. 2 of the drawings, as at 21, and is provided with a suitable stub similar in all respects to stubs 2 and 2', of course the value-indications being altered to correspond with the value of the ticket. The ticket 21 is necessarily slightly modified in arrangement from ticket 1, but involves the same principle. At the inner end of the ticket is preferably arranged a series of graduated figures, as "1," "2," "3," "4," "5," and "6," provided with the words "Trip check" opposite the same, thus indicating the number of trips for which the ticket may be used. Near the opposite end of the ticket are similarly-graduated figures with the words "Transfer check" for indicating and permitting the ticket to be used as a transfer. Any suitable directions and regulations of the company 30 may be printed in the central space, as 22. Below the space 22 and running longitudinally of the ticket are arranged graduated figures, as at 23 and 24, indicating hours and minutes, respectively. Beneath the said graduated figures are arranged a plurality of lines running longitudinally and transversely of the ticket, producing longitudinal and transverse blocks or blank spaces, as 25. A suitable dividing-line, as 26, may be provided 35 for separating the figures 23 from those in the series 24, thereby separating the blocks or spaces 25 beneath the hour-figures from those beneath the minute-figures. The space beneath the minute-figures is again divided by 40 a suitable line 27 and the numerals indicating fractions of an hour repeated on either side of such line, one of said sides being marked "A. M." and the other "P. M." for limiting the time of the transfer to the forenoon or afternoon. At the same time it is limited to the fraction of an hour. At the outer end of ticket 21 is provided a plurality of detachable coupons, as 28 28, which bear corresponding serial numbers to that of the ticket 45 and stub.

Of course it will be apparent that ticket 21 may be provided, if desired, with a similar calendar as that shown at 6 in Fig. 1 and with any of the other features of ticket 1, as may 50 be found preferable.

The ticket 21 may be issued either by the office of the company or by the conductor, and when presented for the first time will be perforated at the point of numeral "1" in 55 the "Trip-check" series. If the passenger does not desire a transfer, the conductor next

punches the numeral "1" of the "Transfer-check" series, whereby the use of the first number of the series of trips to be had on the said ticket 21 will be destroyed as a transfer. 70 The conductor next removes one of the coupons 28 and, retaining the same, returns the ticket to the passenger. The next time the ticket is presented numeral "2" of the "Trip-check" series will be perforated, and should the passenger desire a transfer, presuming the hour to be 8.30 p. m., the blocks 25 will be perforated opposite the numeral "2" of the "Trip-check" series and at the same time opposite the numeral "8" of the "hour" series, and the block opposite the numeral "30" of the "minute" series of the "P. M." side is also perforated, the said block being also opposite the numeral "2" of the "Transfer-check" series, as seen at 29. The conductor 85 then removes one of the coupons 28 and returns the ticket to the passenger. On presenting the ticket as a transfer to the conductor of the connecting-line the said ticket will be perforated at the point of the numeral 90 "2" of the "Transfer-check" series.

It has been found necessary to provide coupons 28 in order to make the ticket 21 good on any line without regard to which line is issued the same, the said coupon being returned 95 to the company as a voucher that the passenger has been carried on the ticket 21.

Although I have specifically set forth a particular embodiment of the present invention, yet I do not wish to be understood as limiting 100 myself to the exact form, shape, arrangement, or design of the present ticket, but shall feel at liberty to deviate therefrom within the spirit and scope of my invention.

Having thus described my invention, what 105 I claim as new, and desire to secure by Letters Patent, is—

1. A book of tickets, each of said tickets forming a leaf thereof, stubs detachably carrying said tickets, means securing said stubs 110 together, and indications on each of said stubs showing the total value of its corresponding ticket plus the value of all of the preceding tickets, and the total value of all the subsequent tickets, substantially as described. 115

2. The combination with a plurality of combined tickets and transfers, of stubs detachably secured thereto and adapted to be secured together, each of said tickets and its stub being provided with a corresponding serial number, and indications on each of said stubs showing the total value of its corresponding ticket plus the value of all of the preceding tickets, and also showing the total value of all of the subsequent tickets, substantially as described. 120 125

In testimony whereof I hereunto affix my signature in presence of two witnesses.

FREDERICK W. GILLARD.
